SPOOL

Joseph K. Taylor, Plainfield, N. J., assignor to
Sonoco Products Company, Hartsville, S. C., a
corporation of South Carolina

Application April 3, 1933, Serial No. 664,236

4 Claims. (Cl. 242—122)

This invention relates to spools, particularly to spools utilized in the textile industry as supporting cores for thread windings or packages.

The object of the invention is to provide a novel spool and a novel method of fabricating and assembling the same, the resulting spool as an article of manufacture being light in weight, of rugged construction, mathematically correct and balanced so as to facilitate the winding and unwinding of thread thereon or therefrom, and relatively inexpensive. The spool may be of the single headed or double headed type as desired, spools of both types being used in large numbers in the textile industry. The methods of fabricating the component elements of the spool are such that these elements may be made at a minimum of expense and may be assembled together to form the completed article with great ease and facility.

Without departure from the spirit and scope of the invention, various embodiments thereof may be devised, two of which are illustrated in the accompanying drawing and will be herein-after described in detail, by way of example.

In the drawing:

Figure 1 is an axial section through a completed spool of the single headed type constructed in accordance with the invention;

Figure 2 is a plan view of the same; and

Figure 3 is an axial section through a modified type of spool.

The spool, in both of its forms, or in still further forms which may be devised in accordance with the invention to comply with the requirements of individual users, comprises essentially four elements, the barrel or central cylindrical member 10, which is generally a tube of paper, wood, fiber, or metal, a conical base member 11, an annular end disc 12, and a cylindrical spacing or abutment member 13. Preferably the conical member 11 or, more properly, the frusto-conical member 11, is formed of thin metal as indicated in Figure 1, the annular end disc 12 of paper or fiber, and the spacing member 13 of the same material. It will be understood, however, that in the fabrication of these last mentioned elements other materials may be employed if desired so long as these materials produce a resulting article having the necessary light weight, balance, rigidity, and ruggedness.

The end disc 12 is an annular member, the interior diameter of which is the same as the exterior diameter of the tube or barrel 10, and the outer periphery of which is truly concentric

with the periphery of its central aperture. The frusto-conical metallic base 11 has its circular edge closely embracing the exterior cylindrical surface of the barrel 10 and its lower margin curved around the outer edge of the end disc 12 as shown. The tubular spacer 13 has its outer annular edge surface disposed in a plane transverse to the axis of the spool and resting against the adjacent parallel inner surface of the end disc 12. The opposite end of member 13 is frusto-conical and lies closely against the adjacent surface of the conical base 11. It is the function of the spacing or abutment member 13, which is rigidly secured to the barrel 10, to firmly support the upper margin of the conical base 11 against downward movement due to pressure of the thread package or winding which the spool supports when in use. The lower end of member 13 also comprises an abutment supporting the inner margin of the annular end disc 12 against inward displacement.

The parts just described may be easily fabricated separately by well-known processes at little expense as these parts are extremely simple and may be made upon machines of standard type. The several elements of the spool may be assembled in various ways, but preferably I first slide the member 13 onto the barrel member 10 until it occupies the position in which it is shown in the drawing. It is secured in this position either by means of glue or adhesive, stitches of metal or fiber thread, rivets, or in any other convenient and inexpensive but nevertheless secure manner. The conical base member 11 is then slipped over the barrel and moved downwardly along the same until it contacts with the upper frusto-conical surface of the spacing member 13. The annular end disc 12 is then positioned as shown, resting against the lower end of the bracing member 13. Finally the lower outer margin of the conical base 11 is curved around the circular outer periphery of end disc 12 by any suitable spinning or swaging operation, the annular end disc being thereby retained firmly in position. The article is then ready for use.

If a double headed spool is to be fabricated, parts in all respects similar to parts 11, 12, and 13 above described are assembled with the barrel at its opposite end. In such case, of course, it will be necessary to first slip over the barrel the conical member similar to the base 11 and to then add the spacing or abutment member 13 and finally the end disc 12, after the member 13 has been attached to the barrel in proper position.

Of course, the conical base assembled with the opposite end of the barrel is oppositely directed, likewise the member corresponding to abutment 13, so that the completed spool has end discs at opposite ends and inwardly directed frusto-conical thread receiving surfaces, as will be understood by one skilled in the art.

In Figure 3 of the drawing a single headed spool constructed in accordance with the principles of the invention, but of somewhat different materials, is illustrated in axial section. Here the barrel 20 is formed of a material which permits it to be upset or turned over at its ends to form locking shoulders, one of which is indicated at 20'. Such a barrel may conveniently be formed of a paper sheet made into tubular form by winding upon a mandrel. The conical base 21 is non-metallic, preferably being a base formed of compressed paper together with a binding material, such, for instance, as is disclosed in application Serial No. 619,758, filed June 28, 1932, in the name of Charles K. Dunlap. The member 23 may be formed of any suitable material, such, for instance, as paper, and the end disc 22 may be conveniently fabricated of fiber. Member 23 is secured to the barrel in any well-known manner, the end disc 22 being clamped or firmly retained between the outer end of this member and the turned-over portion 20' of barrel 20. The outer periphery of the end disc 22 is beveled so as to fit snugly against the conical inner surface of base 21, and a suitable adhesive is employed to secure these two surfaces firmly together. A suitable adhesive may also be employed to secure the cylindrical inner edge surface of base 21 to the outer surface of barrel 20 and also to attach member 21 to member 23 where these two members contact with each other. In this form of the invention, where it is desired to form a spool with two heads, similar parts are applied to the opposite end of the barrel but in reverse order. The final operation of assembling this opposite end will be, of course, the heading over of the opposite end of the tubular barrel 20.

A spool constructed in accordance with this invention has at all times perfect alignment of conical base, or bases, and barrel, that is, perfect coincidence of the axes of these members, which is highly advantageous to its user, as will be appreciated by those familiar with textile machinery. The end discs shown firmly anchor the outer edges of the conical bases to the barrel so that no tilting of these bases can occur relatively to the

axis of the barrel, and hence the angle of taper of all elements of the outer conical surfaces of the bases will remain constant throughout the life of the spool. Other forms of the invention may be devised by slightly modifying the details of construction of the spools disclosed by way of example or by the selection of somewhat different materials, depending upon the uses to which the spool is to be put.

5

Having thus described the invention, what is claimed as new and desired to be secured by Letters Patent is:

1. In a spool, in combination, a cylindrical barrel, a spacing or abutment member encircling the barrel and secured thereto, an annular end disc also encircling the barrel, the inner margin of said disc abutting against the outer end of said member, and a frusto-conical base, the outer edge of which engages the outer periphery of said end disc and the inner periphery of which contacts with the barrel and the end of said member.

2. In a spool, in combination, a cylindrical barrel, a tubular spacing or abutment member enveloping the barrel and rigidly attached thereto, an annular end disc encircling the barrel, the inner margin of said disc abutting the outer end of said member, and a frusto-conical base, the outer margin of which engages and is secured to the outer periphery of said end disc and the circular inner edge of which contacts with the barrel, the inner margin of said base resting upon the inner end of said member and being supported thereby.

3. In a spool, in combination, a cylindrical barrel, a tubular spacing or abutment member enveloping the barrel at one end thereof and rigidly attached thereto, an annular end disc encircling the barrel, the inner margin of said disc abutting the outer end of said member, and a frusto-conical metallic base comprising a sheet of thin ductile metal, the outer margin of which is curved around the outer periphery of said disc and closely engages the same, and the circular inner edge of which contacts with the barrel and the inner end of said member.

4. A spool comprising a barrel, an annular end disc at the end thereof, a frusto-conical base, and an abutment or spacing member affixed to the barrel, one end of said member supporting said end disc and the other end thereof supporting the inner margin of said base.

JOSEPH K. TAYLOR.
